UNITED STATES PATENT OFFICE.

LEWIS D. NELSON, OF COLDWATER, MICHIGAN, ASSIGNOR OF ONE-HALF TO ROBERT M. NEALE, OF UNION CITY, MICHIGAN.

FILLING MACHINE.

Application filed June 18, 1925. Serial No. 37,955.

- This invention relates to improvements in filling machines.
- My improvements are especially designed by me for filling bags with cement, lime or other heavy materials, the embodiment illustrated being especially designed for the handling of cement. My improvements are, however, readily adapted and desirable for use in handling other materials.
- 10 The main objects of this invention are:
- First, to provide an improved bag filling machine which is automatic in operation and is controlled by the weight of the filled bags.
- 15 Second, to provide in a bag filling machine an improved delivery mechanism which is of very large capacity.
- Third, to provide an improved filling machine which is not likely to become clogged in use.
- 20 Fourth, to provide an improved filling machine which is easily operated, it only being required that the operator shall place the empty bags or receptacles upon the filling spout.
- 25 Objects pertaining to details and economies of construction and operation of my invention will definitely appear from the detailed description to follow.
- 30 I accomplish the objects by the devices and means described in the following specification. The invention is clearly defined and pointed out in the claims.
- 35 A structure embodying the features of my invention is clearly illustrated in the accompanying drawing forming a part of this application, in which:
- 40 Fig. I is a fragmentary front elevation of a filling machine embodying the features of my invention, the hopper being omitted and the lower portion of the frame being broken away.
- 45 The machine illustrated is a duplex machine comprising two filling and weighing mechanisms.
- 50 Fig. II is a fragmentary side elevation looking from the left of Fig. I, portions being broken away for convenience in illustration.
- 55 Fig. III is a fragmentary rear perspective view showing details of the operating mechanism.

Fig. IV is a fragmentary front perspective showing the parts in one discharging position.

Fig. V is a fragmentary perspective view of certain parts shown in Fig. IV with the spout in released or tripped position.

Fig. VI is a detail section on a line corresponding to line 6-6 of Fig. VII showing details of the ejector or discharge mechanism.

Fig. VII is a detail section on a line corresponding to line 7-7 of Fig. VI.

Fig. VIII is a detail view partially in vertical section on a line corresponding to line 8-8 of Fig. III showing details of the driving mechanism.

Fig. IX is a detail view partially in section on a line corresponding to line 9-9 of Fig. III showing further details of the driving or operating mechanism.

Fig. X is a detail view partially in section on a line corresponding to line 10-10 of Fig. III.

Fig. XI is a fragmentary view showing details of the feed valve operating mechanism.

Fig. XII is a detail view mainly in section on a line corresponding to line 12-12 of Fig. VII showing still further details of the feed valve operating mechanism.

Fig. XIII is a horizontal section on line 13-13 of Fig. VI showing details of the rotor.

Fig. XIV is a front view of the combined spout carrier and control member.

Fig. XV is a detail view showing details of the carrier actuating means.

Fig. XVI is a horizontal section corresponding to that of Fig. VII of a modified form of ejector mechanism.

Fig. XVII is a detail section showing further details of the actuating mechanism.

In the drawing the sectional views are taken looking in the direction of the little arrows at the ends of the section lines and similar numerals of reference refer to similar parts throughout the several views.

Referring to the drawing I provide a main supporting frame 1 of suitable character to support the hopper 2 and the operating mechanisms. The structure shown in Fig. I is a double unit machine with the units arranged side by side. However, as the units are duplicates a description of one will be sufficient.

The material may be supplied to the hopper 2 by any suitable means. The hopper has a discharge neck 3 for each unit, the

neck in effect being a part of the hopper. At the bottom of the hopper is an ejector cylinder 4 open at the top to the hopper.

The rotor designated generally by the numeral 5 is disposed horizontally in the bottom of the cylinder and comprises a bottom plate or side member 6 and a top plate or side member 7 having a central inlet opening 8 therein with the blades 9 arranged between these side members. The blades 9 are bolted to the radially disposed webs 10 extending between the side disks or plates of the rotor and connecting the same.

The bottom plate of the rotor is provided with a central conical portion 11 disposed below the opening 8 in the top plate, the inner ends of the blades overlapping or extending upon the sides of this conical portion, which constitutes a deflector for directing the material passing through the opening 11 outwardly between the blades.

The ejector cylinder has a tangentially disposed discharge port 12 and a peripheral clearance space or pocket 13 lying beyond the periphery of the rotor and opening to the cylinder above the top plate of the rotor, as shown in Fig. VI. The discharge passage is provided with a pair of slide valves 15 and 16, the valve 15 being operated by a mechanism to be hereinafter described, while the valve 16 is manually operated from the hand lever 17 on the rockshaft 18 which is provided with an arm 19 connected to the valve, see Fig. XII.

35 The upper ends of these valves project into a chamber 20 which opens into the port 12, this chamber having a clearance opening 21. The chamber and clearance opening are of such size as to provide a clearance for 40 the valves, that is, to provide for the escape of any material that may be lifted by the valves in opening the same. Both valves are shown in open position in Fig. XII and in closed position in Fig. VII.

45 Adjacent the discharge of the cylinder I provide a wear plate 22 which is in the form of a segment disposed in a recess 23 in the side of the cylinder. The rear end of this plate is bolted at 24 to the cylinder, its other 50 end being adjustably supported by the screw 25 so that it may be accurately adjusted relative to the rotor or into proper relation with the rotor to insure effective discharge of the material. This is a very desirable feature 55 as it is found that a substantial clearance at this point detracts from the efficiency of the rotor, and also that there is a tendency for rapid wear at this point, particularly when handling such material as cement. This adjustable wear plate segment 22 provides for adjustment for wear.

The cylinder is provided with a hand-hole 26 with a removable cover plate 27 arranged so that the hand hole provides a recess at 65 the periphery of the rotor, affording access

to the rotor should occasion require, and this recess also serves to collect slugs or worn grinding balls and the like which may be in the cement. These grinding balls or slugs are thrown into the pocket by centrifugal force and collected, preventing undue wear or breakage of the rotor.

The bottom plate 6 of the rotor is provided with a plurality of rearwardly curved clearing blades 28 which extend outwardly from the packing 29. This packing is disposed between the rotor, which has a conical recess 30 to receive the same, and the collar-like flange 31 on the rotor shaft 32. The rotor is threaded upon the upper end of the rotor shaft as indicated in Fig. VI clamping the packing 29 between the rotor and this collar, the packing rotating with the rotor as a unitary part thereof. The bottom of the cylinder is recessed at 33 to receive the collar 31, the edge of the packing projecting beyond and overlying the edge of the recess. This effectively protects the shaft bearing 34, it being found that with the packing and clearance blades on the under side of the rotor the material is effectively prevented from reaching the rotor shaft bearings.

With the parts thus arranged, any excess of material passing to the rotor is returned to the cylinder or opening above the rotor through the clearance opening 13. This prevents clogging and is of particular merit in the handling of cement, lime or other heavy materials which have a tendency to pack. It also greatly reduces the likelihood of the machine becoming clogged in the event of continued operation with either of the feeding valves closed. I, however, provide a cut-off valve 35 the purpose of which is to cut off the hopper when it is desired to clear the rotor for repair purposes and the like, or to remove the rotor cylinder should occasion require.

The material is controlled by a weighing mechanism which in the structure illustrated comprises a scale beam 36 pivoted at 37, see Figs. IV and V. The scale beam is provided with a weight 38 and with an auxiliary scale bar 39 having an adjustable weight 40 for accuracy in adjustment. Suspended from the scale beam is a platform carrying frame 41. The mounting for this platform carrying frame will be hereinafter described.

The platform comprises a pair of sections 42 pivoted at 43 to the sides 44 of the platform to project inwardly in opposed relation, these platform sections being held normally in erected position by the coiled springs 45 shown conventionally in Fig. I. The platform has a back wall 46. The tension of the springs is such as to sustain a weight approximately equal to that of the filled bag so that as soon as the platform is subjected to the full weight of the filled bag, the sections drop downwardly as indicated

in Fig. I to discharge the bag. The scale beam also carries the spout carrier 47 which has hangers 48 and 49 engaging the arms of the scale beam 36, the scale beam being 5 forked at its inner end.

The platform frame yoke 41 is pivoted at 50 on the carrier 47, thus being indirectly mounted on the scale beam. This carrier has a counterweight 51 disposed above its 10 pivot. This counterweight is provided with a stop member 52 which is pivoted at 53 and provided with downwardly projecting stops 54. An adjustable support 55 is provided for the outer or swinging end of the 15 stop member. The weight has a pair of pins 56 which coact with the stop member, the stop member having a central recess 57 adapted to alternately receive these pins. The pin engaging the recess 57 serves as a 20 positive means for holding the parts in position at each end of the stroke thereof until released by the actuation of the scale beam. The carrier is thereby lowered until the stop member engages the rest 55, the pin 56 25 moving out of engagement with the slot allowing the carrier to swing.

The carrier is provided with a pair of spouts 58 pivoted at 59 and projecting forwardly above the scale platform to receive 30 the bags as indicated by dotted lines in Fig. VI. These spouts are held in erected position by the latches 60 which are pivoted at 61 and have upwardly projecting trip arms 62 adapted to engage the tripping lugs 63 35 as the carrier moves downwardly with the scale beam, the spouts being provided with keepers 64 with which the latches engage, see Fig. VI. The tripping lugs 63 are secured for vertical adjustment and are slotted 40 at 65, attaching screws 66 engaging these slots.

When the latches are disengaged on the initial downward movement of the scale beam, the spouts are free to tilt as shown 45 in Fig. V. The spouts are automatically returned to their erected position when the bags are discharged by means of the coiled springs 67. When the bags slip from the spouts, the full weight thereof coming upon 50 the platform members 42, causes them to open allowing the filled bag to fall to a suitable chute or carrier not illustrated.

The bags are held upon the spouts by the bag holders 68 which are pivoted at 69 on the brackets 70 by which the spouts are carried. The bag holders 68 have rearwardly projecting arms 71 with cams 72 thereon which engage the tripping pins 73 as the spout swings forwardly upon being released, thereby disengaging the bag holders with a rearward swinging movement and the bag 60 holders swing forwardly to engage the bags. The outward movement of the bags upon the spouts only serves to cause the bag 65 holders to grip more firmly. To insure the

releasing of the bag holders I provide springs 67 which yieldingly urge the cam arm 71 against the trip pin 73.

The spouts are alternately brought into operative relation to the discharge port or 70 opening of the ejector by a swinging movement of the carrier, this swinging movement in the embodiment illustrated being accomplished as follows:

The carrier is provided with an upwardly 75 facing yoke 74 having seats 75 at the ends thereof to receive the roller 76 on the actuating lever 77, which is pivotally mounted at 78 and provided with an arm 79 connected by the link 80 to an arm 81 on the rockshaft 82 which, in the structure illustrated, is disposed through an opening 83 through the hopper neck 3, see Fig. VI. The rockshaft 82 has an arm 84 thereon to which the actuating pitman 85 is connected. This pitman is actuated by a cam 86 secured to the gear 87, the lower end of the pitman being held in position by the pin 88 engaging the slot 89. The gear 87 is mounted on the shaft 90. The slot 89 is formed in the 89 head 91 on the end of the pitman with which the cam 86 coacts. The gear 87 is driven from the gear 92 on the shaft 93.

The gear 87 on the shaft 90 is connected 95 to the main driving shaft 94 by means of the gear 95 on the shaft 93 coacting with the pinion 96 on the shaft 94. This shaft 94 is provided with the driving pulley 97. The rotor shaft 32 is connected to the driving shaft 94 by the beveled gears 98, see 100 Fig. VIII.

The gear 92 is intermittently driven, it being rotatable on the shaft 93 and driven from the ratchet 99 which is secured to the shaft, the pawl 100 coacting with the ratchet 105 being pivotally mounted at 101 on the cam 102. The cam is provided with a sleeve 103 connected to the gear. The driving pawl is controlled by a trip 104 on the lever 105 which is pivoted at 106 and pivotally connected at 107 to the rear side of the rear wall 46 of the scale platform. The downward movement of the scale platform releases the pawl 100, allowing it to engage the driving ratchet 99 thereby driving the gear 92 until the pawl again engages the trip 104. 110

To insure a complete actuation the lever 105 is provided with an arm 108 which is engaged by the cam 102, thereby moving 120 the lever 105 a complete stroke at each operation. The actuation of the gear 87 through the connections described swings the actuating lever 77, thereby actuating the carrier, which, however, is held in its actuated position by the stop member 52 until the scale beam is lowered sufficiently to disengage the stop pin 56 from the recess 57 of the stop member. The carrier is thus positively 125 actuated, 130

To close the feed valve during this shifting operation and to open it when the parts have completed the cycle, bringing the second spout to filling position, I provide 5 a cam 109 which has a pawl carrying arm 110 secured thereto, the pawl 111 being pivoted at 112 on the arm to coact with the driving ratchet 113 which is secured to the shaft.

10 The control lever 105 has an arm 114 with a trip 115 thereon adapted to coact with the pawl, the pawl being released on the downward movement of the scale beam to close the valve. The trip 115 is returned to pawl 15 releasing position when the scale beam swings upwardly to initial position. The cam 109 has a lift 116 with a sharp face so that on the initial movement of the cam the arm 117 pivoted at 118 and carrying the link 20 119 is permitted to fall. This link is connected to the valve actuating lever 120. Positive action of the valve is insured by the spring 121.

25 To prevent overthrow of the parts the cam 109 is provided with a friction brake 122 which coacts with the hub 123 on the cam. A similar brake 125 is provided for the gear 92. The friction of these brakes is such that the parts are stopped as soon as 30 the driving pawls are released.

With the parts thus arranged the operation of my improved filling machine is as follows: The material is supplied to the hopper by any suitable means. With a bag in 35 position on the spout 58, which is in operative position, the machine is started and the material delivered by the ejector until sufficient weight is delivered to the bag to actuate the scale, the downward movement of 40 the scale bringing the latch arm 62 into engagement with the trip 63, releasing the spout so that it may tilt forwardly. This forward tilting movement releases the bag holder as has been described.

45 This, however, does not take place until after the carrier stop mechanism has been disengaged, as described, by the downward movement of the carrier. Further, the downward movement of the platform actuates the control lever 105 disengaging the driving pawls for the carrier shifting mechanism, as described, and for closing the feed valve. The control lever is actuated a full stroke so that the carrier shifting mechanism 50 is free to operate.

As soon as the downward stroke is completed the parts are returned to their initial position by the weight of the scale beam, and during this return movement the yoke 55 on the carrier is brought into engagement with the shifting lever which is swung to its opposite position, thereby swinging the carrier. As the carrier moves upwardly, the stops on the counterweight engage with the 60 stop member securely holding the parts in

position until again released by the downward movement occasioned by the load of the filled bag.

In the modification shown in Fig. XVI the ejector cylinder 126 is provided with two 70 discharge ports 127 disposed in opposed relation so that a filling unit may be operated on each side of the machine. Otherwise, the parts are substantially as described.

My improved filling machine is of very 75 large capacity, is automatic in its operation, the operator being merely required to place the bags upon the spouts, and it is not likely to become clogged. The hand operated valve 16 is provided as an emergency valve in the 80 event that some part of the machine becomes broken or out of order, and, as stated, the cut-off valve 35 is provided to permit repairs of the rotor or the removal of the rotor cylinder. 85

While the embodiment illustrated is especially designed for the handling of cement, lime and like heavy materials, my improvements are very readily adapted for the handling of various other materials. I have not attempted to illustrate or describe various modifications and adaptations which I contemplate as I believe the disclosure made will enable those skilled in the art to embody or adapt the same as may be desired.

Having thus described my invention, what I claim as new and desire to secure by Letters Patent is:

1. In a structure of the class described, the combination of a feed means including a feed valve, a cam for actuating said valve, a weighing mechanism including a scale beam, a platform operatively associated with said scale beam, a carrier pivotally mounted on said scale beam for vertical and oscillating movement, a yoke on the upper end of said carrier having seats on opposite sides of the carrier pivot, a pivotally mounted actuating lever coacting with said yoke to actuate said carrier as the lever is actuated and to hold it in its actuated position when said scale beam is in its initial position, an actuating cam for said lever, a rock shaft provided with an arm operatively connected to said actuating lever, a pitman operatively associated with said control cam, said rock shaft having a second arm to which said pitman is connected, a pair of driving ratchets, driven members operatively connected to said valve and lever actuating cams and provided with pawls coacting with said driving ratchets, a pivotally mounted trip lever operatively connected to said platform and provided with tripping tappets coacting with said pawls, a cam operatively associated with one of said driven members coacting with said trip lever to insure complete actuation of the mechanism, a counterweight on said actuating lever, a pivotally mounted stop member provided with a cen-

tral stop recess and a pair of spaced stops, stop pins on said counterweight adapted to alternately engage with said stop recess and with said stops on said stop member, said 5 stop member being provided with a support for its swinging end and whereby the stop pins remain in engagement with the stop recess during the initial downward movement of the scale beam, and spouts pivotally 10 mounted on said carrier to be alternately brought into operative relation with said feed means.

2. In a structure of the class described, the combination of a feed means including a 15 feed valve, a cam for actuating said valve, a weighing mechanism including a scale beam, a platform operatively associated with said scale beam, a carrier pivotally mounted on said scale beam for vertical and oscillat- 20 ing movement, a yoke on the upper end of said carrier having seats on opposite sides of the carrier pivot, a pivotally mounted actuating lever coacting with said yoke to actuate said carrier as the lever is actuated 25 and to hold it in its actuated position when said scale beam is in its initial position, an actuating cam for said lever, a rock shaft provided with an arm operatively connected to said actuating lever, a pitman operatively 30 associated with said control cam, said rock shaft having a second arm to which said pitman is connected, a pair of driving ratchets, driven members operatively connected to said valve and lever actuating cams 35 and provided with pawls coacting with said driving ratchets, a pivotally mounted trip lever operatively connected to said platform and provided with tripping tappets coacting with said pawls, and a cam operatively 40 associated with one of said driven members coacting with said trip lever to insure complete actuation of the mechanism.

3. In a structure of the class described, the combination of a weighing mechanism 45 including a scale beam, a platform operatively associated with said scale beam, a carrier pivotally mounted on said scale beam for vertical and oscillating movement, a yoke on the upper end of said carrier having seats on the opposite side of the carrier pivot, a pivotally mounted actuating lever coacting with said yoke to actuate said carrier as the lever is actuated and to hold it 50 in its actuated position when said scale beam is in its initial position, means for actuating said lever comprising an actuating cam, a driving ratchet, a driven member operatively connected to said lever actuating cam and provided with a pawl coacting with said 55 driving ratchet, a pivotally mounted trip lever operatively connected to said platform and provided with a tripping tappet coacting with said pawl, a cam operatively associated with said driving ratchet coacting 60 with said trip lever to insure complete actuation of the mechanism.

65

tuation of the mechanism, a pivotally mounted stop member provided with a central stop recess and a pair of spaced stops, stop pins on said actuating lever adapted to alternately engage with said stop recess and 70 with said stops on said stop member, said stop member being provided with a support for its swinging end whereby the stop pins remain in engagement with the stop recess during the initial downward movement of 75 the scale beam, and spouts mounted on said carrier to be alternately brought into operative relation with said feed means.

4. In a structure of the class described, the combination of a weighing mechanism 80 including a scale beam, a platform operatively associated with said scale beam, a carrier pivotally mounted on said scale beam for vertical and oscillating movement, a yoke on the upper end of said carrier having seats on the opposite side of the carrier pivot, a pivotally mounted actuating lever coacting with said yoke to actuate said carrier as the lever is actuated and to hold it 85 in its actuated position when said scale beam is in its initial position, means for actuating said lever comprising an actuating cam, a driving ratchet, a driven member operatively connected to said lever actuating cam and provided with a pawl coacting with said 90 driving ratchet, a pivotally mounted trip lever operatively connected to said platform and provided with a tripping tappet coacting with said pawl, and a cam operatively associated with said driving ratchet coacting 95 with said trip lever to insure complete actuation of the mechanism.

5. In a structure of the class described, the combination of a feed means including a feed valve, a cam for actuating said valve, a weighing mechanism including a scale beam, a platform operatively associated with said scale beam, a carrier pivotally mounted on said scale beam for vertical and oscillating movement, means for oscillating 100 said carrier comprising a cam, driving ratchets, driven members operatively connected to said valve and carrier actuating cams, pawls mounted on said driven members to coact with said driving ratchets, a pivoted trip lever connected to said platform and provided with pawl disengaging tappets, and spouts mounted on said carrier to be alternately brought into operative relation 105 with said feed means.

6. In a structure of the class described, the combination of a weighing mechanism including a scale beam, a platform operatively associated with said scale beam, a carrier pivotally mounted on said scale beam for vertical and oscillating movement, means for oscillating 110 said carrier comprising a driven member, a driving ratchet, a pawl mounted on said driven member to coact with said driving ratchet, a pivoted trip lever opera- 115

120

125

130

tively connected to said platform and provided with a pawl disengaging tappet, a friction brake operatively associated with said driven member for preventing the over-
5 throw thereof, and spouts mounted on said carrier to be alternately brought into operative relation with said feed means.

7. In a structure of the class described, the combination of a weighing mechanism including a scale beam and platform, a carrier operatively associated with said scale beam for vertical and oscillating movement, means for oscillating said carrier comprising a driven member, a driving ratchet, a pawl 10 mounted on said driven member to coat with said driving ratchet, a pivoted trip lever connected to said platform and provided with a pawl disengaging tappet, and spouts mounted on said carrier to be alternately brought into operative relation with said feed means.

8. In a structure of the class described, the combination of a feed means including a feed valve, a valve actuating cam, a weighing mechanism including a scale beam, a carrier pivotally mounted on said scale beam for vertical and oscillating movement, means for oscillating and holding said carrier in its actuated position controlled by the movement of said scale beam, spouts mounted on said carrier to be alternately brought into operative relation with said feed means, a driving ratchet, a driven member, a pawl 25 mounted on said driven member to coat with said driving ratchet, a trip lever provided with a pawl disengaging tappet and operatively associated with said scale beam, and a friction brake operatively associated with said valve actuating cam for preventing the over-
30 throw thereof.

9. In a structure of the class described, the combination of a feed means including a feed valve, a valve actuating cam, a weighing mechanism including a scale beam, a carrier pivotally mounted on said scale beam for vertical and oscillating movement, means for oscillating and holding said carrier in its actuated position controlled by the movement of said scale beam, spouts mounted 45 on said carrier to be alternately brought into operative relation with said feed means, a driving ratchet, a driven member, a pawl mounted on said driven member to coat with said driving ratchet, a trip lever provided with a pawl disengaging tappet and operatively associated with said scale beam.

10. In a structure of the class described, the combination of a feed means including a feed valve, a cam for actuating said valve, a weighing mechanism including a scale beam, a platform operatively associated with said scale beam, a driving ratchet, a driven member operatively connected to said valve actuating cam and provided with a pawl coating with said driving ratchet, a pivotally

mounted trip lever operatively connected to said platform and provided with a tripping tappet coating with said pawl, and a friction brake operatively associated with said valve actuating cam for preventing the over-
70 throw thereof.

11. In a structure of the class described, the combination of a feed means including a feed valve, a cam for actuating said valve, a weighing mechanism including a scale beam, a platform operatively associated with said scale beam, a driving ratchet, a driven member operatively connected to said valve actuating cam and provided with a pawl coating with said driving ratchet, and a pivotally 75 mounted trip lever operatively connected to said platform and provided with a tripping tappet coating with said pawl.

12. In a structure of the class described, the combination of a feed means including a feed valve, a valve actuating cam, a weighing mechanism, a driving ratchet, a driven member operatively associated with said valve actuating cam, a pawl mounted on said driven member to coat with said driving ratchet, a pivoted trip lever provided with a pawl disengaging tappet and operatively associated with said scale beam, and a friction brake operatively associated with said valve actuating cam for preventing the over-
85 throw thereof.

13. In a structure of the class described, the combination of a feed means including a feed valve, a valve actuating cam, a weighing mechanism, a driving ratchet, a driven member operatively associated with said valve actuating cam, a pawl mounted on said driven member to coat with said driving ratchet, and a pivoted trip lever provided with a pawl disengaging tappet and operatively associated with said scale beam.

14. In a structure of the class described, the combination of a feed means including a feed valve, a weighing mechanism including a scale beam, a carrier pivotally mounted on said scale beam for vertical and oscillating movement, means for actuating said carrier controlled by the movement of said scale beam, spouts mounted on said carrier to be alternately brought into operative relation with said feed means, and means for quickly closing said valve controlled by said scale beam.

15. In a structure of the class described, the combination of a feed means including a feed valve, a cam for actuating said valve, a weighing mechanism including a scale beam, a carrier pivotally mounted on said scale beam for vertical and oscillating movement, a yoke on the upper end of said carrier having seats on opposite sides of said carrier pivot, a pivotally mounted indicating lever coating with said yoke to actuate said carrier as the lever is actuated and to hold it in its actuated position when said scale

beam is in its initial position, an actuating cam for said actuating lever, a control cam operatively associated with said weighing mechanism to insure the full stroke thereof and operatively connected to said valve actuating and lever actuating cams, a driving and control means for said control cam operatively associated with said weighing mechanism, spouts mounted on said carrier to be alternately brought into operative relation with said feed means, an arm on said carrier projecting above its pivot, a counterweight on said arm, a pivotally mounted stop bar, stops on said counterweight coacting with said stop bar, and a rest for the swinging end of said stop bar, said stops being disengaged by the downward movement of the scale beam.

16. In a structure of the class described, the combination of a feed means, a weighing mechanism including a scale beam, a carrier pivotally mounted on said scale beam for vertical and oscillating movement, a yoke on the upper end of said carrier having seats on opposite sides of the carrier pivot, a pivotally mounted actuating lever coacting with said yoke, means for actuating said lever, an upwardly projecting arm on said lever provided with a pair of stop pins, a pivotally mounted stop member provided with a pair of spaced stops coacting with said pins and a central stop recess adapted to be alternately engaged by said pins, said stop member being provided with a support for its swinging end and whereby the stop pin is disengaged from said recess during the initial downward movement of the scale beam, and spouts mounted on said carrier to be alternately brought into cooperative relation with said feed means.

17. In a structure of the class described, the combination of a feed means including a feed valve, a cam for actuating said valve, a weighing mechanism including a scale beam, a carrier pivotally mounted on said scale beam for vertical and oscillating movement, a yoke on the upper end of said carrier having seats on opposite sides of said carrier pivot, a pivotally mounted actuating lever coacting with said yoke to actuate said carrier as the lever is actuated and to hold it in its actuated position when said scale beam is in its initial position, an actuating cam for said actuating lever, a control cam operatively associated with said weighing mechanism to insure the full stroke thereof and operatively associated with said valve actuating cam and said lever actuating cam, a driving and control means for said control cam operatively associated with said weighing mechanism, and spouts mounted on said carrier to be alternately brought into operative relation with said feed means.

18. In a structure of the class described, the combination of a weighing mechanism

including a scale beam, a carrier pivotally mounted on said scale beam for vertical and oscillating movement, a yoke on the upper end of said carrier having seats on opposite sides of said carrier pivot, an actuating lever coacting with said yoke to actuate said carrier as the lever is actuated and to hold it in its actuated position when said scale beam is in its initial position, an actuating cam for said actuating lever, a control cam operatively associated with said weighing mechanism to insure the full stroke thereof and operatively connected to said lever actuating cam, a driving and control means for said control cam operatively associated with said weighing mechanism, spouts mounted on said carrier to be alternately brought into operative relation with said feed means, an arm on said carrier projecting above its pivot, a counterweight on said arm, a pivotally mounted stop bar, stops on said counterweight coacting with said stop bar, and a rest for the swinging end of said stop bar, said stops being disengaged by the downward movement of the scale beam.

19. In a structure of the class described, the combination of a weighing mechanism including a scale beam, a carrier pivotally mounted on said scale beam for vertical and oscillating movement, a yoke on the upper end of said carrier having seats on opposite sides of said carrier pivot, an actuating lever coacting with said yoke to actuate said carrier as the lever is actuated and to hold it in its actuated position when said scale beam is in its initial position, an actuating cam for said actuating lever, a control cam operatively associated with said weighing mechanism to insure the full stroke thereof and operatively connected to said lever actuating cam, a driving and control means for said control cam operatively associated with said weighing mechanism, and spouts mounted on said carrier to be alternately brought into operative relation with said feed means.

20. In a structure of the class described, the combination of a feed means including a feed valve, a weighing mechanism, a carrier mounted on said weighing mechanism for vertical and oscillating movement, spouts mounted on said carrier to be alternately brought into operative relation with said feed means, a yoke on the upper end of said carrier having seats on the opposite sides of the carrier pivot, a pivotally mounted actuating lever coacting with said yoke to actuate said carrier as the lever is actuated and to hold it in its actuated positions when the weighing mechanism is in its initial position, a driving means, operating connections therefor to said lever, operating connections for said driving means to said feed valve, and a control means for said driving means including a member opera-

tively associated with said weighing mechanism.

21. In a structure of the class described, the combination of a feed means, a weighing mechanism, a carrier mounted on said weighing mechanism for vertical and oscillating movement, spouts mounted on said carrier to be alternately brought into operative relation with said feed means, a yoke on the upper end of said carrier having seats on the opposite sides of the carrier pivot, a pivotally mounted actuating lever coacting with said yoke to actuate said carrier as the lever is actuated and to hold it in its actuated positions when the weighing mechanism is in its initial position, a driving means, operating connections therefor to said lever, and a control means for said driving means including a member operatively associated with said weighing mechanism.

22. In a structure of the class described, the combination of a feed means including a feed valve, a weighing mechanism, a carrier mounted on said weighing mechanism for vertical and oscillating movement, spouts mounted on said carrier to be alternately brought into operative relation to said feed means, a yoke on the upper end of said carrier having seats on opposite sides of the carrier pivot, a pivotally mounted actuating lever coacting with said yoke, an actuating cam operatively connected to said lever, a driving means operatively connected to said cam, means for closing said valve operatively connected to said driving means, and a control means for said driving means operatively associated with said weighing mechanism.

23. In a structure of the class described, the combination of a feed means, a weighing mechanism, a carrier mounted on said weighing mechanism for vertical and oscillating movement, spouts mounted on said carrier to be alternately brought into operative relation to said feed means, a yoke on the upper end of said carrier having seats on opposite sides of the carrier pivot, a pivotally mounted actuating lever coacting with said yoke, an actuating cam operatively connected to said lever, driving means operatively connected to said cam, and a control means for said driving means operatively associated with said weighing mechanism.

24. In a structure of the class described, the combination of a feed means including a feed valve, a weighing mechanism, a carrier mounted on said weighing mechanism for vertical and oscillating movements, means for automatically oscillating said carrier, spouts mounted on said carrier to be alternately brought into operative relation to said feed means, a valve actuating means, and a control means for said carrier oscil-

lating means and feed valve actuating means operatively associated with said weighing mechanism.

25. In a structure of the class described, the combination of a feed means, a weighing mechanism, a carrier mounted on said weighing mechanism for vertical and oscillating movements, means for automatically oscillating said carrier, spouts mounted on said carrier to be alternately brought into operative relation to said feed means, and a control means for said carrier oscillating means operatively associated with said weighing mechanism.

26. In a structure of the class described, the combination of a feed means including a feed valve, a weighing mechanism, a carrier mounted on said weighing mechanism for vertical and oscillating movement, spouts mounted on said carrier to be alternately brought into operative relation with said feed means, means for oscillating said carrier including a driving means, operating connections for said driving means to said feed valve, and a control means for said driving means including the member operatively associated with said weighing mechanism.

27. In a structure of the class described, the combination of a feed means, a weighing mechanism a carrier mounted on said weighing mechanism for vertical and oscillating movement, spouts mounted on said carrier to be alternately brought into operative relation with said feed means, means for oscillating said carrier including a driving means, and a control means for said driving means including the member operatively associated with said weighing mechanism.

28. In a structure of the class described, the combination of a feed means including a valve, a weighing mechanism, an adjustably mounted delivery member provided with a plurality of spouts adapted to be successively brought into operative relation with said feed means, means for automatically adjusting said delivery member, a driving means therefor, operating connections for said driving means to said feed valve, and a control means for said driving means operatively associated with said weighing mechanism whereby said valve and delivery member are automatically actuated upon the actuation of the weighing mechanism.

29. In a structure of the class described, the combination of a feed means, a weighing mechanism, a carrier mounted on said weighing mechanism for vertical and oscillating movement, spouts mounted on said carrier to be alternately brought into operative relation with said feed means, means for holding said carrier in position when the weighing mechanism is at its initial position adapted to be released on the initial downward movement of said weighing mecha-

- nism, means for oscillating said carrier including a driving means, means for controlling said carrier oscillating means operatively connected to the weighing mechanism to be actuated on the down stroke thereof, means for compelling a complete stroke of the weighing mechanism including a driving member, and a control means for such driving member operatively associated with said weighing mechanism.
30. In a structure of the class described, the combination of a feed means, a weighing mechanism, a carrier mounted on said weighing mechanism for vertical and oscillating movement, spouts mounted on said carrier to be alternately brought into operative relation with said feed means, means for oscillating said carrier including a driving means, means for controlling said carrier oscillating means operatively connected to the weighing mechanism to be actuated on the down stroke thereof, means for compelling a complete stroke of the weighing mechanism including a driving member, and a control means for such driving member operatively associated with said weighing mechanism.
31. In a structure of the class described, the combination of a feed means, a weighing mechanism, a carrier mounted on said weighing mechanism for vertical and oscillating movement, spouts mounted on said carrier to be alternately brought into operative relation with said feed means, means for holding said carrier in position when the weighing mechanism is at its initial position adapted to be released on the initial downward movement of said weighing mechanism, means for oscillating said carrier including a driving means, and means for controlling said carrier oscillating means operatively connected to the weighing mechanism to be actuated on the down stroke thereof.
32. In a structure of the class described, the combination of a feed means, a weighing mechanism, a carrier mounted on said weighing mechanism for vertical and oscillating movement, spouts mounted on said carrier to be alternately brought into operative relation with said feed means, means for oscillating said carrier including a driving means, and means for controlling said carrier oscillating means operatively connected to the weighing mechanism to be actuated on the down stroke thereof.
33. In a structure of the class described, the combination of a weighing mechanism, a carrier mounted on said weighing mechanism for oscillating movement, spouts mounted on said carrier to be alternately brought into feeding position, means for oscillating said carrier including a driven member and driving connections for said driven member to said carrier oscillating
- means controlled by the actuations of said weighing mechanism, and means for holding said carrier in feeding position when the scale beam is in its initial position adapted to be released on the initial downward movement of said weighing mechanism.
34. In a structure of the class described, the combination of a weighing mechanism, a carrier mounted on said weighing mechanism for oscillating movement, spouts mounted on said carrier to be alternately brought into feeding position and means for oscillating said carrier including a driven member and driving connections for said driven member to said carrier oscillating means controlled by the actuations of said weighing mechanism.
35. In a structure of the class described, the combination of a feed means, a weighing mechanism, an adjustably mounted delivery member provided with a plurality of spouts adapted to be successively brought into operative relation with said feed means, means for automatically adjusting said delivery member, a driving means therefor, and a control means for said driving means operatively associated with said weighing mechanism whereby said delivery member is automatically actuated upon the actuation of the weighing mechanism.
36. In a structure of the class described, the combination of a weighing mechanism feed means, a spout carrier provided with a plurality of spouts adjustably associated with said feed means, and means for automatically adjusting said carrier operatively associated with said weighing mechanism to be actuated upon the actuation of said weighing mechanism.
37. In a structure of the class described, the combination of feed means, a weighing mechanism, a spout carrier mounted on said weighing mechanism, a spout pivotally mounted on said carrier, a latch for holding said spout in its erected position adapted to be disengaged on the downward movement of the carrier, a pivoted bag holder coacting with said spout and having a cam arm, a member with which said cam arm engages on the downward movement of said spout whereby the bag holder is disengaged, and a return spring for said spout.
38. In a structure of the class described, the combination of feed means, a weighing mechanism, a spout carrier mounted on said weighing mechanism, a spout pivotally mounted on said carrier, a latch for holding said spout in its erected position adapted to be disengaged on the downward movement of the carrier, and a return spring for said spout.
- In witness whereof I have hereunto set my hand.
- LEWIS D. NELSON.
